UNITED STATES PATENT OFFICE.

LEWIS S. WEST, OF ROCHESTER, NEW YORK.

REFRIGERATOR-CAR CONSTRUCTION.

Application filed July 19, 1922. Serial No. 576,055.

To all whom it may concern:

Be it known that I, LEWIS S. WEST, a citizen of the United States, residing at Rochester, in the county of Monroe and State of New York, have invented a certain new and useful Improvement in Refrigerator-Car Constructions, of which the following is a full, clear, concise, and exact description, reference being had to the accompanying drawings, forming a part of this specification.

This invention relates to improvements in refrigerator car construction.

The general practice in refrigerator car construction is to employ spring-pressed heat insulation or packing between the two pivoted doors on each side of the car and the lintel and jamb, together with a wide threshold metal wear plate. The object of the insulation is of course to prevent the transmission of heat from the exterior to the interior of the car to thereby eliminate freezing of perishable contents during the winter time and undue heating of the contents in warmer weather. Due to the necessity of trucking the contents of the car across the threshold it is not feasible to employ the spring-pressed packing at the threshold and to minimize wear, it has been customary to employ the wide metal threshold plate. Furthermore, it has been found that there is less danger of the moisture collecting and freezing at the threshold where metal plates are employed, which is another reason for eliminating the use of the spring-pressed packing found on the other edges of the door.

Operators of refrigerator cars have been subject to many and expensive damage claims arising from injury to the contents of the car adjacent the threshold, which is due to the fact that the heat is readily transmitted from the exterior to the interior of the car by means of the usual metal threshold plate, which has heretofore been extended for a width in excess of the thickness of the usual insulated refrigerator door.

One object of my invention is to provide, in a refrigerator car construction, practical means of a simple and inexpensive nature which will eliminate or at least reduce very appreciably the possibility of transmitting heat from the exterior to the interior of the car across the threshold joint to thereby minimize the damage claims above referred to. At the same time, it is an object of my

invention to preserve, so far as possible, the wear-resisting advantages of the usual threshold plate.

In the drawings forming a part of this specification, Figure 1 is a side elevational view of a portion of a refrigerator car showing the doors in closed position and in which are embodied my improvements. Figure 2 is a horizontal sectional view corresponding to the section line 2—2 of Figure 1. And Figure 3 is a vertical sectional view corresponding to the section line 3—3 of Figure 1, the operating and locking means being omitted.

In said drawings forming a part of this specification, the side of the car is shown as provided with a rectangular door opening of the usual size, said door opening being defined by a lintel 10, jambs 11—11 and a threshold, hereinafter more specifically described. The door opening is adapted to be closed by two pivoted doors 12 and 13, hinged as indicated at 14—14 to swing about vertical axes coinciding with the planes of the opposed faces of the respective jambs. As customary in refrigerator car construction, the lintel 10 is inwardly and downwardly beveled as indicated at 10° in Figure 3. The lintel 10 and each jamb 11 are provided with longitudinally extending recesses 114 in each of which is mounted a preferably wooden backing strip 15 normally yieldingly pressed outward by a series of coil springs 16, each spring seated in a suitable socket bored into the lintel or jamb as the case may be. Extended over the faces of the lintel and door jambs 11 are layers of felt and canvas packing as indicated at 17 in Figures 2 and 3, it being understood that said packing is nailed or otherwise secured to the respective fixed structure on each side of the corresponding recess 114. With this arrangement, it is evident that when the doors are forced to closed position, a tight heat-insulating joint will be formed between the edges of the doors and the lintel and door jambs. As customary in refrigerator car construction, the walls of the car are suitably heat-insulated as also are the doors, the latter being of appreciable thickness as clearly shown in Figure 3.

The floor of the car is indicated at 18 and the threshold is outwardly and downwardly beveled, the same being composed in part by one floor board 18a and a threshold wood plank 19. The bottom edges of

the doors 12 and 13 are correspondingly beveled so as to provide a tight fit with the threshold when the doors are in closed position. In carrying out my invention, I 5 provide a longitudinally extended metal threshold wear plate 20 which is countersunk flush within the threshold as clearly shown in Figure 3, said plate 20 being held in place by wood screws 21-21. It will 10 be noted from an inspection of Figure 3 that the wear plate 20 is appreciably narrower than the thickness of the doors and is located at a point intermediate the inner and outer faces of the doors so that there 15 is wood on opposite sides of the threshold plate 20, thereby preventing any appreciable transmission of heat across the threshold joint when the doors are closed. At the same time, it will be noted that the plate 20 20 is so located as to effectively minimize wear of the wood parts on opposite sides thereof. Extensive actual use of my improvements as herein disclosed, has shown that the arrangement is effective for the purposes 25 herein set forth and has, in the case of one refrigerator car operating company, decreased damage claims very materially, arising from the causes mentioned.

As customary, the door 12 is first moved 30 to closed position and locked by a detent 24 shown in Figure 1, the door 13 being forced home last and moved to fully closed position by means of an operating shaft 25 having a handle 26 of well known construction.

I claim:

1. In a refrigerator car having a door

opening defined by lintel, jambs and wooden threshold, the combination with a door adapted to close said opening; of heat-insulating packing located between said door and the adjacent portion of the car defining the door opening; and a threshold metallic wear plate inserted in said wooden threshold, said plate being of lesser width 45 than the thickness of said door, whereby, at least one edge of said plate which extends parallel with the door when the latter is in closed position, is disposed intermediate the inner and outer planes of the door to 50 thereby prevent transference of heat from one side of the door to the other side.

2. In a refrigerator car having a door opening defined by lintel, jambs and wooden threshold, the combination with a 55 pair of oppositely swinging pivotal doors adapted to close said opening; of spring-pressed heat-insulating packing in each of the joints between the doors and the lintel and jambs; and a metallic threshold wear plate countersunk within said wooden threshold, said wear plate being of lesser width than the thickness of the doors and located at a point intermediate the inner and outer planes of the doors when the latter are in closed position.

In witness that I claim the foregoing I have hereunto subscribed my name this 5th day of July, 1922.

L. S. WEST.
